2 SHEETS—SHEET 2.

UNITED STATES PATENT OFFICE.

CHARLES MÜLLER, OF ZURICH, SWITZERLAND.

DRAWING APPARATUS.

Application filed April 2, 1920. Serial No. 370,694.

To all whom it may concern:

Be it known that I, CHARLES MÜLLER, a citizen of the Republic of Switzerland, residing at Zurich, Leonhardstrasse 13, Switzerland, have invented certain new and useful Improvements in Drawing Apparatus; and I do hereby declare the following to be a clear, full, and exact description of the invention, such as will enable others skilled 10 in the art to which it appertains to make and use the same, reference being had to the accompanying drawing, and to letters or figures of reference marked thereon, which form a part of this specification.

15 This invention relates to drawing apparatus wherein two links are provided parallel to each other and adapted to act as parallel guide for squares, rules and the like.

20 The object of the present invention is to improve and simplify such apparatus.

To this end at least one guide is secured to an edge of a drawing board, and mounted traversable thereon is a carriage, preferably wheeled, that serves to carry parallel pivoted levers connected to a holder or support for drawing instruments such as a rule, square, triangle, curve or the like.

Several modes of carrying the invention 30 into effect are shown by way of example on the accompanying drawing, on which:

Fig. 1 is a plan view of a first construction embodying the invention;

Fig. 1^a is a detail view showing the connection of a sleeve and wheel frame;

Fig. 2 is a section on line A—B of Fig. 1;

Fig. 3 is a section on line C—D of Fig. 1;

Fig. 4 is a plan of a modified arrangement;

40 Fig. 5 is a view of a second modification;

Fig. 6 is a section through the instrument carrier showing holding means for a pencil or the like.

Fig. 7 shows a modification of a detail.

45 Referring first to the exemplification of the invention shown in Figs. 1-3, 1 designates a rod provided with division marks, a slide 3 which can be fixed by a set screw 2 is slidably mounted on rod 1. The rod is 50 carried near its ends in sleeves 4, in which it can be adjusted in an axial direction and fixed by set screws 5. Each sleeve is mounted on a frame 6 provided with two wheels 7 to form a carriage. The wheels are 55 guided on parallel rails 8, which, in the example shown, are fixed by any suitable

means in the plane of drawing of a drawing board used in a horizontal position. Preferably one of the carriage frames 6 is arranged to be angularly adjustable against 60 rod 1, which adjustment enables the carriage to run on rails 8 which are not exactly parallel to each other, the sleeve 4 being mounted on a pin 4^a loose in the carriage 6, Fig. 1^a. On pins 10 fixed to the 65 slide 3 the ends of two links 11 are rotatably mounted whilst their other ends are connected to a disc 12. The latter is provided with a circular scale 13, which can be adjusted against an index mark 14, ar- 70 ranged on a projecting part of a bracket 15 which may be turned on and fixed to said disc, a square 16 being detachably secured to said bracket and serving as drawing instrument. A sleeve 18 slides on the rod 1 75 and can be adjusted along said rod by a set screw 17 (Fig. 2), a drawing pencil 20 passes through a lug of sleeve 18 and is held therein by a set screw 19. The links 11 are connected to disc 12 in an articulated 80 manner shown in Fig. 3. The articulation of this joint may be suspended by tightening a throw-over nut 21, whereafter links 11 are rigidly connected to disc 12. On moving square 16 in any direction over the 85 plane of the drawing by moving knob 22 by hand, links 11 will always remain parallel to each other and likewise all the positions of the square 16 will be parallel to each other. Long parallel lines may be 90 drawn by means of the drawing pencil 20 by simply causing the carriages to travel along the rails.

The constructional example shown in Fig. 4 differs from that described above inasmuch as the rails 8^a are not placed on the top of the plane of drawing 9 but are secured to the edges of the drawing board by clamps 23. This arrangement is likewise suited for horizontally used drawing boards. 95

In the case of a vertical drawing board 9^a (Fig. 5) the rails 8^b are fixed on upper and lower edges 24 of the board. The upper carriage frame 6^a is fixed to rod 1, whilst the lower carriage frame 6^a is guided 105 by said rod and pressed against the lower rail 8^b by a spring 25. In this arrangement at least one of the links 11^a is extended beyond its fulcrum 10 and carries an adjustable counterweight 26 for counter-balancing 110 the weight of square 16 in every position. The two discs 15 and 12 and their handle

22 are provided with a bore for the reception of a pencil that may be held by a set-screw 36.

As previously described the wheel frames 5 6 in Figs. 1 and 4 are arranged so that they can only be used with horizontal drawing boards 9, and the wheel frames 6^a of Fig. 3 can only be used with vertical drawing boards 9^a. Fig. 6 shows now a modification 10 of the wheel frame arranged to be used with horizontal as well as with vertical drawing boards 9^a. An inverted V-shaped rail 8^a is fixed to an edge of the drawing board 9^a. Wheel frames 6^b run along said rail each 15 fitted with two pairs of wheels 7^a and 7^b arranged at an angle against each other. A sleeve 4 is provided on each wheel frame in which the rod 1 is fixed by means of screw 5.

I claim:

20 1. In a drawing apparatus, a rail for attachment parallel to the edge of a drawing board, a wheeled carriage traversable on said rail, a pair of parallel levers pivoted at one end to said carriage, means to which the other end of said pair of levers is pivotally connected and a fastening on said means to hold a drawing instrument for directing the drawing of lines.

25 2. In a drawing apparatus, a rod, wheels 30 on each end of said rod, rails on which said wheels are traversable, a slide adjustable along said rod, a pair of parallel levers pivoted at one end to said slide, a disc connected to the other end of said pair of levers, and means on the disc to hold a drawing instrument.

35 3. In a drawing apparatus, a rod, a wheel carriage adjustable along each end of said rod, rails for said carriages, a slide adjust-

able along said rod, a disc, a pair of parallel levers pivoted at one end to said slide and at the other end to said disc and means on said disc to hold a drawing implement. 40

4. In a drawing apparatus, a rod, a wheeled carriage at each end of said rod and 45 adjustable along said rod, at least one of said carriages being angularly adjustable with respect to said rod, a slide adjustable along said rod, a disc, a pair of parallel levers connected at one end to said slide and 50 at the other end to said disc and means on said disc for holding a drawing instrument.

5. In a drawing apparatus, a rod, a wheeled carriage on each end of said rod and adjustable therewith and angularly adjustable thereto, rails for said carriages a slide adjustable along said rod between the carriages, a pair of parallel levers secured at one end to said slide, a disc adjustably connected to the other end of said lever pair, 55 a second disc adjustable with respect to the first disc and means on said second disc to hold a drawing instrument.

6. In a drawing apparatus, rails for attachment to opposite sides of a drawing 65 board, a rod, wheeled carriages on said rails longitudinally and angularly adjustable with respect to said rod, a slide on said rod, parallel levers pivoted at one end to said 70 slide, a disc to which the other end of said pair of levers is adjustably connected, a second disc angularly adjustable to the first disc, and means on said second disc for holding a rule and the like.

In testimony that I claim the foregoing 75 as my invention, I have signed my name.

CHARLES MÜLLER.
